UNITED STATES PATENT OFFICE.

WILLIAM H. GREENFIELD, OF PHILADELPHIA, PENNSYLVANIA.

DESIGN FOR AN ELECTRIC HEATER.

Application filed September 24, 1928. Serial No. 28,263. Term of patent 3½ years.

To all whom it may concern:

Be it known that I, WILLIAM H. GREENFIELD, a citizen of the United States, residing in Philadelphia, in the county of Philadelphia and State of Pennsylvania, have invented a new, original, and ornamental Design for Electric Heaters, of which the following is a specification, reference being had to the accompanying drawings, forming part thereof.

In the drawings Fig. I is a front view of an electric heater showing my new design; and

Fig. II is a rear view of the same.

I claim:

The ornamental design for an electric heater, as shown.

WILLIAM H. GREENFIELD.
